E. O. VEBRAATEN

BOLSTER

Filed April 21, 1923

INVENTOR.

E.O.Vebraten

BY
Watson E. Coleman
ATTORNEY.

UNITED STATES PATENT OFFICE.

ELMER O. VEERAATEN, OF VANG, NORTH DAKOTA.

BOLSTER.

Application filed April 21, 1923. Serial No. 633,663.

To all whom it may concern:

Be it known that I, ELMER O. VEERAATEN, a citizen of the United States, residing at Vang, in the county of Cavalier and State 5 of North Dakota, have invented certain new and useful Improvements in Bolsters, of which the following is a specification, reference being had to the accompanying drawings.

This invention relates to improvements in bolsters and more particularly to the improvements in the bolster construction employed in wagons or the like.

An important object of the invention is 15 to provide in the bolster construction a novel and improved stake mounting whereby the stake is firmly held in elevated position but may be readily shifted to inoperative position to permit unloading of the 20 vehicle.

A further object of the invention is to provide an extensible bolster, the length of which may be varied as desired.

A still further object of the invention is 25 to provide an attachment for bolsters applicable to the present construction of bolster and by means of which the bolster can be made extensible, the attachment embodying a novel and improved stake mounting 30 whereby the stakes are readily shiftable to operative or inoperative position and are positively held in the latter position.

These and other objects I attain by the construction shown in the accompanying 35 drawings, wherein for the purpose of illustration I have shown a preferred embodiment of my invention and wherein:—

Figure 1 is a perspective view of a bolster constructed in accordance with my invention;

Figure 2 is a fragmentary perspective showing the stake moved to the inoperative position;

Figure 3 is a sectional view taken through 45 the end of the bolster and the stake mounting;

Figure 4 is a transverse sectional view taken substantially centrally of the bolster; and

50 Figure 5 is a perspective view of the stake locking plate.

Referring now more particularly to the drawings, the numeral 10 generally indicates a bolster having extending from each end 55 thereof spaced vertically disposed parallel

flanges 11, connected at their top ends with horizontally disposed flanges 12 which are oppositely directed. Pivotally mounted between the flanges 11 and substantially filling the space therebetween is the lower end of 60 a stake 13, the pivot being indicated at 14 and being adjacent the lower ends of the vertical flanges 11. The horizontal flanges 12 are provided with slots 15 communicating with vertical slots 16 formed in the upper 65 ends of the vertical flanges 11, the slots 15 and 16 being immediately adjacent the outer face of the stake 13 when the same is in operative or vertical position.

Mounted in the stake 13 is a bolt 17 the 70 head of which is arranged at the outer face of the stake, this bolt having mounted thereon between the head and the face of the stake a plate 18, the bolt extending through a slot 19 formed in the plate. The plate 18 75 is substantially T shaped, the slot 19 being formed in the stem thereof and this stem being of a width slightly less than the distance between adjacent faces of the flanges 11. The upper end of the head 20 of the plate 80 is provided with an outwardly extending horizontal flange 21 and this head is of greater width than the distance between the plates 11, accordingly, when the stake is vertically arranged and the plate 18 85 moved downwardly thereon, the head 20 of this plate will engage in the slots 15 and 16 locking the stake against movement between the flanges, the flange 21 serving as a handle for manipulation of the plate and 90 by its engagement with the horizontal flanges 12 to limit downward movement of the plate. The slot 19 is of sufficient length so that by engaging the flange 21 of the plate the plate may be elevated so that the 95 lower edge of the head clears the upper ends of the horizontal flanges 12, at which time the stake 13 may be rotated to inoperative position to permit unloading of the vehicle of which the bolster forms a part.

In the construction of the bolster 10 I 100 preferably employ as a body the ordinary bolster 22 of the vehicle, this bolster being cut off just inwardly of the ordinary stake openings thereof and having formed therein in adjacent each end an opening 23 and having extended therethrough at its approximate center a transversely disposed guide bolt 24. With this bolster as reconstructed I employ a pair of channel iron frames 105 110

and 26, the frame 26 having the channel thereof closely fitting and slidably receiving the bolster 22 and the channel of the frame 25 closely receiving the frame 26 and slid-
5 able thereon. Each of the frames 25 and 26 has formed in the sides thereof longitudinally extending slots 27 through which the guide bolt 24 is directed, these slots permitting longitudinal shifting of the frames
10 25 and 26 but positively limiting this movement. These side arms are further provided with a series of longitudinally spaced openings 28 arranged in aligned pairs, adapted for selective alignment with the
15 openings 23 of the ends of the bolster and when so aligned combining with the bolster to receive securing pins 29 of any desired construction.

In the construction of the frames 25 and
20 26 the side arms of each of these frames at one end thereof are bent inwardly toward one another, as indicated at 30, and subsequently outwardly to form the spaced flanges 11 hereinbefore referred to. The bight portions
25 at these ends are continued outwardly and notched, as indicated at 31, the upper edges of the portions of the arms forming the flanges 11 being secured to the bight portion, the bight portion thus serving to form
30 the horizontal flanges 12 hereinbefore referred to. From the foregoing it will be seen that by the addition of the frames 25 and 26 a bolster is provided which is longitudinally extensible, which may be secured at
35 in adjusted position and which affords at each end thereof a novel and improved stake mounting. It will furthermore be obvious that this structure is capable of some change and modification without materially de-
40 parting from the spirit of my invention and I accordingly do not limit myself to such specific structure as hereinbefore set forth except as hereinafter claimed.

I claim:—

45 1. In an extensible bolster, a bolster body having a guide bolt extending therethrough approximately centrally thereof, a pair of channel iron frames, one slidably fitting the bolster and longitudinally shiftable thereon and the other slidably fitting the first named frame, said frames having slots therein receiving the ends of said guide bolt, said bolster body having openings formed therein adjacent the ends thereof, said frames being provided with aligned pairs of longitudinally spaced openings selectively alignable with the openings of the bolster body and retaining pins adapted for extension through aligned openings of the frames and body.
50
55
60

2. In a bolster, a stake mounting comprising a pair of vertically disposed spaced flanges extending outwardly from the ends of the bolster and between which the stake is pivotally mounted and swingable to oper-
65

ative and inoperative positions, horizontal flanges connected with the upper ends of the vertical flanges and extending in opposite directions therefrom and having slots therein, and a plate slidable upon the stake having portions engageable in said slots when the stake is in vertical position. 70

3. In an extensible bolster, a bolster body having a guide bolt extending transversely therethrough approximately centrally thereof, a pair of inverted channel iron frames, one slidably fitting the bolster and longitudinally shiftable thereon and the other slidably fitting the first named frame, said frames having slots formed in the arms thereof receiving the ends of said guide bolts, said bolster body having openings formed therein adjacent the ends thereof, said frames being provided in the arms thereof with aligned pairs of longitudinally spaced openings selectively alignable with the openings of the bolster body and retaining pins adapted for extension through aligned openings of the frame and body. 85

4. In a bolster, a stake mounting comprising a pair of vertically disposed flanges extending outwardly from the ends of the bolster and between which the stake is pivotally mounted and swingable to operative and inoperative position, said flanges having vertical slots formed therein and opening through the upper ends thereof aligning with the outer face of the stake when in vertical position, and a plate slidable upon the outer face of the stake having portions engageable in said slots when the stake is in vertical position. 95

5. In a bolster, a stake mounting comprising a pair of vertically disposed flanges extending outwardly from the ends of the bolster and between which the stake is pivotally mounted and swingable to operative and inoperative position, said flanges having vertical slots formed therein and opening through the upper ends thereof aligning with the outer face of the stake when in vertical position, and a plate slidable upon the outer face of the stake having portions engageable in said slots when the stake is in vertical position, and horizontal flanges secured to the upper ends of the vertical flanges and extending in opposite directions therefrom, said horizontal flanges having slots formed therein communicating with the slots of their respective vertical flanges 110 and into which the outer edges of said plate extend. 115

6. In a bolster, a stake mounting comprising a pair of vertically disposed flanges extending outwardly from the ends of the bolster and between which the stake is pivotally mounted and swingable to operative and inoperative position, said flanges having vertical slots formed therein and opening through the upper ends thereof align- 120
125
130

ing with the outer face of the stake when in vertical position, and a plate slidable upon the outer face of the stake having portions engageable in said slots when the stake is in vertical position, and horizontal flanges secured to the upper ends of the vertical flanges and extending in opposite directions therefrom, said horizontal flanges having slots formed therein communicating with the slots of their respective vertical flanges and into which the outer edges of said plate extend, said plate being provided with a horizontal flange engaging the first named horizontal flanges to limit downward movement of the plate.

7. In a bolster, a bolster body, a pair of inverted channel iron frames slidable upon the bolster body and upon one another and

shiftable thereon to extended positions, means for securing said frames in extended positions, each of said frames having its bight portion at the outer end thereof notched, the arms of the frames adjacent such outer ends being bent inwardly and then outwardly to form spaced flanges, the upper ends of which are secured to the bight portion at the edges of the notch, a stake pivotally mounted between said flanges and swingable to operative and inoperative position, a stake slidable upon the plate and coacting slots formed in the bight portions of the frame and said flanges receiving said plate when the stake is in operative position.

In testimony whereof I hereunto affix my signature.

ELMER O. VEBRAATEN.
